(57) CLAIM

The ornamental design for a surface configuration of a center console for a vehicle, as shown and described.

DESCRIPTION

This application is related to the following co-pending applications, of the inventor, filed on even date herewith: Application Serial No. 29/197,289, entitled "Surface Configuration of a Dashboard for a Vehicle"; Application Serial No. 29/197,288, entitled "Surface Configuration of a Dashboard for a Vehicle"; and Application Serial No. 29/197,287, entitled "Surface Configuration of a Center Console for a Vehicle".

FIG. 1 is a front view of a surface configuration of a center console for a vehicle according to my novel design; and, FIG. 2 is a perspective view of the surface configuration of a center console for a vehicle according to my novel design. The broken lines are for illustrative purposes only and form no part of the claimed design.

1 Claim, 2 Drawing Sheets

FIG. 1

FIG. 2
